UNITED STATES PATENT OFFICE.

JOHN W. DELANO, OF SKOWHEGAN, MAINE, ASSIGNOR OF ONE-HALF TO
GEORGE H. CLARKE, OF SAME PLACE.

TOOL FOR CLINCHING HORSESHOE-NAILS.

SPECIFICATION forming part of Letters Patent No. 365,974, dated July 5, 1887.

Application filed April 8, 1887. Serial No. 234,103. (No model.)

To all whom it may concern:

Be it known that I, JOHN W. DELANO, a citizen of the United States, residing at Skowhegan, in the county of Somerset and State of Maine, have invented certain new and useful Improvements in Tools for Clinching Horse-shoe-Nails; and I do hereby declare the following to be a full, clear, and exact description of the invention, such as will enable others skilled in the art to which it appertains to make and use the same.

My invention relates to that class of tools which are used for the purpose of turning down and clinching the point of a horse-shoe-nail after the same has been driven through the foot of the horse. Many tools for this purpose have previously been used and patented; but in all of them the design has been to hold the tool horizontally, or nearly so, while turning down and clinching the nail. By the use of clinchers operating in this way it has always been difficult, and in some cases quite impossible, to clinch the nails on all parts of the hoof, on account of the awkward position in which the hands must be held to manipulate the tool. When the farrier held the horse's foot in his lap, it has always been difficult to follow around the shoe with one of these clinchers holding the tool in a position substantially parallel with the face of the shoe. This is particularly true when handling restless horses, in which case it is always desirable and necessary to keep both hands as near the leg and foot as possible in order to guard against any sudden movement of the horse. When doing this work with the old form of tool, as I have pointed out, the positions of the hands were such that the foot and leg of the horse could not be easily controlled.

My invention is designed to obviate this difficulty; and it consists of a clinching-tool having a straight jaw for resting against the bottom of the shoe, a curved jaw for turning the points of the nails, and two handles which are

at right angles, or nearly so, with the straight jaw, the construction of the tool being such that when the tool is in operation it is held in a vertical position, the hands being at all times near the horse's legs.

My invention is illustrated in the accompanying drawing, which represents the tool in position to clinch a nail in a horse's foot.

A is the straight jaw, and B the curved jaw, and A' and B' are the respective handles.

C represents the horse-shoe, and D the nail.

When the jaw A is placed flat on the head of the nail to be clinched and the handles are spread apart, the curved jaw will be in position to clinch the point of the nail and the handles will be vertical, or nearly so. The farrier in using the clincher is thus able to keep both hands in close proximity to the horse's legs, working his way around the shoe without changing them from substantially this position.

In shoeing nervous horses this tool is a desirable one for the reason which I have pointed out—namely, that the hands are kept well in toward the leg of the horse, so that they are in position to seize the leg at the least motion.

I claim—

As a new article of manufacture, a horse-shoe-nail clincher having a straight jaw to be placed under the shoe, a curve jaw adapted to turn the point of the nail, and two handles substantially perpendicular to the plane of the working-face of said straight jaw, whereby the clincher, when operated, is held in a vertical position, or nearly so, substantially as shown.

In testimony whereof I affix my signature in presence of two witnesses.

JOHN W. DELANO.
